UNITED STATES PATENT OFFICE

JOSEPH L. BECKER, OF STILLWATER, MINNESOTA

SNOWPLOW ATTACHMENT FOR TRACTORS

Application filed December 10, 1928. Serial No. 324,894.

This invention relates to attachments for tractors and the primary object is to provide a practical, efficient and comparatively simple snow-plow, and means for conveniently 5 and effectively attaching it to the tractor whereby it may be pushed along to laterally convey the snow from the road, sidewalk, or other surface to be cleared. A further object is to so construct the connection between 10 the plow and the tractor that the plow, while being pushed, will have sufficient freedom for vertical and tilting action over sidewalk and road irregularities, yet will not have a tendency, when meeting with unusual resistance, 15 to buckle up or cause an upward tilt of the fore end of the tractor. These and more specific objects will be disclosed in the course of the following specification, reference being had to the accompanying drawings, in which: 20 Fig. 1 is a side elevation of my improved snow-plow attachment, showing it as applied to a common and well known type of tractor. Fig. 2 is a plan view of the device as seen when detached from the tractor. Fig. 3 is a sectional elevation on the line 3-3 in Fig. 2. Fig. 4 is a sectional elevation on the line 4-4 in Fig. 2.

Referring to the drawings more particularly and by reference characters, A designates any common and well known type of tractor. The snow plow illustrated is of the type wherein an angularly disposed single blade 5 is provided with a side board or longitudinally disposed plate 6, although the V-type of plow, which throws the snow to both sides may of course be used with the same effect as far as the present invention is concerned. The members 5 and 6 are reinforced 30 by angle irons 7, and the lower edge of the blade is provided with an adjustable wear plate 8, having angularly disposed slots 9 engaged by bolts 10 secured in the blade 5. Hence, as the plate 8 wears away it may be moved both downwardly and forwardly to properly compensate for such wear. The lower edge of the side plate 6 is provided with shoes 11 that may be replaced when worn away. At its front end the plow 5-6 40 is provided with a rigid, upwardly curved arm 12, which is so designed and arranged that it will raise the point of the plow when it approaches obstructions such as curbs, manholes, etc., thus permitting the plow to properly ride over such obstructions. 55 Rigidly connecting the plow members 5 and 6 is a transversely disposed beam 13, the right end of which is provided with a spring acting brace 14 carrying a wear shoe 15 that supplements the shoes 11 and effects a slightly yieldable ground support for the blade 5. 60 The members 5-6 are further rigidly connected by a pair of vertically spaced, transversely disposed cross bars 16 and 17, connected by spaced pairs of vertical guide rods 65 or braces 18 and 19. Operative in the two rectangular openings formed by the members 16-19, are two push bars 20 and 21, each of which is formed by two angle irons secured together with overlapped flanges. The forward ends of the push bars 20, 21 are pivotally secured, as at 22, to the beam 13, and at their rear ends are pivoted, as at 23, to an angle plate or beam 24 that bolts up under 70 the front end of the tractor. 75 It will be noted that the beams 20 are slightly inclined from the horizontal, and therefore the forward push of the tractor is primarily converted into a forward push on the plow, although there is a slight downward pressure to cause the plow to cling to the ground when in action. The incline of the push bars 20 is also sufficiently slight so that there will be no noticeable tendency of the tractor to crawl over the plow should the latter be stopped, even though the construction disclosed permits an ample floating action of the plow with respect to the tractor. Thus, when slight road irregularities are met with the plow can tilt on the centers 22 80 when passing over the same; and, irregularities that will raise either the plow or the tractor, with respect to the other, will be permitted by the pivots 23. The guide members 18 and 19 retain the push bars, and consequently the plow, in their proper longitudinal positions, and the cross bars 16, 17 limit the pivoting action of the plow and beams 20-21, with respect to each other, yet there is sufficient freedom of action between the 85 90 95 100

various parts to also permit a slight transverse tilting of the plow with respect to the tractor.

To lift the plow out of engagement with the road or walk I provide the connector bracket 24 with a standard 25 to the upper end of which is pivotally secured a lever 26 (see Fig. 1). The front end of this lever is connected by suitable means, such as the link 27, to the plow, and the rear end is adapted, when pulled down, to engage under a hook 28 on the tractor and preferably near the operator's station. When thus lifted the plow is of course raised on the pivots 23, after the push bars first reach the limit of movement permitted between the cross bars 16-17.

It is understood that suitable modifications may be made in the general design and structural details of the invention as herein shown, provided, however, that said modifications come within the spirit and scope of the appended claims.

Having now therefore fully shown and described my invention, what I claim to be new and desire to protect by Letters Patent is:

1. A snow-plow attachment for a tractor comprising a pair of converging plow forming plate members, a transverse beam connecting said members, a pair of push bars pivoted to the beam and extending rearwardly for connection to the tractor, and means adapted to contact with the push bars for limiting the swinging action of the plow with respect to the push bars.

2. A snow-plow attachment for a tractor comprising a plow adapted to be propelled in advance of the tractor, a push device pivotally connected at its front end to the plow, and pivotally connected at its rear end to the tractor, and means carried by the plow for contact above and under the push device for limiting the pivot action of the plow with respect to the push device.

3. A snow-plow for tractors or the like comprising an angularly disposed snow removal blade, a pair of push bars extending rearwardly from and pivotally connected with respect to the blade, means carried solely by the plow so as to be independent of any tractor connection for limiting the up and down movement of the bars with respect to the blade, and means for attaching the bars to a tractor.

4. A snow-plow attachment for a tractor comprising a pair of converging plow-forming plate members, push bars pivotally connected, at their front ends, to the plow, and adapted to be secured at their rear ends to a tractor, and a pair of cross bars connecting the plates, one above and one below the push bars, to limit the vertical action of the bars with respect to the plow.

5. A snow-plow attachment for a tractor comprising a pair of converging plow-forming plate members, push bars pivotally con-

nected, at their front ends, to the plow, and adapted to be secured at their rear ends to a tractor, and a pair of cross bars connecting the plates, one above and one below the push bars, to limit the vertical action of the bars with respect to the plow, and means secured to said cross bars for vertically guiding the push bars.

6. A snow-plow comprising a side plate and an angularly disposed blade joined therewith, wear shoes at the lower edge of the plate, and a wear shoe yieldably mounted adjacent the blade tending to flexibly support the same.

In testimony whereof I affix my signature.

JOSEPH L. BECKER.
